TAPE SUPPORTING MEANS FOR STRAND
COVERING MACHINES

Axel C. Nystrom, Rutherford, and Walter J. Voickhausen, Teaneck, N. J., assignors to Western Electric Company, Incorporated, New York, N. Y., a corporation of New York

Application November 4, 1947, Serial No. 783,874

3 Claims. (Cl. 57—3)

1

This invention relates to material supplying apparatus, and more particularly to an apparatus for supplying tape-like cores to stranding machines for forming switchboard cables.

In the manufacture of switchboard cables, it has been found desirable to produce the cables with flat or oval cross-sectional contours as they may be more readily disposed in the compact areas in switchboard equipment. The insulated electrical conductors of cable of this type are formed about a tape-like material more commonly known as pressboard which may be of various widths depending upon the size of cable to be formed thereon, and more particularly to the number of electrical conductors to be wound spirally thereabout.

An object of the invention is to provide a material supplying apparatus which is simple in structure, efficient in operation, readily adjustable for various sizes of material supplies and easily actuatable for the mounting of the material supplies therein.

With this and other objects in view, the invention comprises a material supplying apparatus including a frame rotatable about its axis and supporting a supply of material on an axis at right angles to the frame axis. Means under the control of an electric switch is provided to rotate the frame in one direction during rotation of the supply of material in another direction and at the same time, means engaging the supply of material causes actuation of the switch to render the rotating means ineffective when the supply of material becomes empty.

More specifically the invention includes a frame in the form of a flyer rotated about its axis to rotate a supply pad of tape-like material about the centerline of a path along which the material is advanced longitudinally.

A brake element is positioned to engage the pad of material and through the combined forces of a plurality of springs create a constant tension in the material by diminishing the brake drag as the pad decreases in size. A rod movable with the brake element carries a handle positioned to actuate a lever which in turn operates a normally closed switch to open the switch and open a circuit to a power means, such as a motor, to stop rotation of the flyer or frame when the pad of material becomes empty.

Other objects and advantages will be apparent from the following detailed description when considered in conjunction with the accompanying drawings, wherein

2

Fig. 1 is a front elevational view of the material supplying apparatus;

Fig. 2 is an end elevational view of the apparatus;

Fig. 3 is an enlarged fragmentary sectional view of the material supporting mechanism of the apparatus;

Fig. 4 is an enlarged fragmentary front elevational view of a portion of the apparatus illustrating the brake element and the switch control means, a portion of this structure being shown in section; and

Fig. 5 is an enlarged sectional view taken along the line 5—5 of Fig. 4.

15 The material supplying apparatus includes a flyer unit indicated generally at 10 rotatable in bearings 11 and 12 supported by mounting brackets 14 and 15. The flyer 10 is in the form of a frame composed of channel members 18 disposed at spaced positions parallel with each other and connected to enlarged head-like portions of shafts 19 and 20 at their ends. The shafts 19 and 20 are journaled in alignment with each other in the bearings 11 and 12. Sleeves 21 and 22 are mounted in aligned apertures 23 and 24 of the channel members 18 to receive annular internally threaded members 25 and 26. The sleeves 21 and 22 and the members 25 and 26 are fixed parts of the frame or channel members 18.

30 Adjustable retaining elements 27 and 28 are externally threaded to be received in their internally threaded members 25 and 26 respectively, and are internally apertured as at 29 and 30 to receive a tubular supporting element or spindle 31. Handles 32 are mounted in the ends of the supporting element 31 whereby the element may be readily removed from the apertures 29 and 30 from either side of the machine. Latches 33 and 34 slide longitudinally in guideways 35 and 36 are normally held in the position shown in Fig. 3 adjacent their respective ends of the supporting element 31 by the force of their respective springs 39 and 40. The springs 39 and 40 are disposed concentric with rods 41 and 42 movable longitudinally in apertured lugs 43 and 44 carried by brackets 45 and 46 which are supported by the channel members 18. The springs 39 and 40 abut their respective lugs 43 and 44 at like ends, their opposite ends engaging outwardly extending handles 47 and 48 which are fixed to the latches 33 and 34, respectively. By moving the handles 47 and 48 to the left (Fig. 3) their respective latches 33 and 34 will be moved away from the ends of

the element 31 freeing it to be removed from the apertures 29 and 30.

The retaining elements 27 and 28 have grooves 49 and 50 therein disposed at spaced positions about their peripheries to receive retaining latches 53 and 54 respectively. The latches 53 and 54 are mounted on the inner ends of rods 55 and 56 which extend through apertures in the brackets 45 and 46. Handles 57 and 58 are mounted on the outer ends of the rods 55 and 56 for use in moving the latches 53 and 54 outwardly free of any of the grooves 49 and 50 where they are held normally by the forces of springs 59 and 60. Aligning pins 61 and 62 carried by the brackets 45 and 46 and entering apertures 63 and 64 in the handles 57 and 58 respectively, hold the latches 53 and 54 against rotation. The pins 61 and 62 serve also to hold the latches 53 and 54 disengaged when the handles are rotated after they are moved outwardly free of the pins. Laterally extending rods or fingers 67 and 68 are carried by the retaining members 27 and 28 to lie adjacent the sides of a pad or supply of material 70.

The shaft 20 carries guide elements 75 to guide the material 76 from the supply pad 70 into a narrow opening through the shaft wherein the material is guided in a path coincident with the axis of rotation of the flyer unit or frame 10 during longitudinal advancement of the material. A sprocket 77 mounted on the shaft 20 is connected to a sprocket 78 of a drive shaft 79 by a chain 80. The drive shaft 79 is supported in suitable bearings 81 and driven by a motor 82 through a sprocket and chain connection 83. In the present embodiment of the invention, the motor 82 is in a circuit 85 with a control switch 86. In actual structure, the necessary relays (not shown) are provided together with the conventional start switch 87 and stop switch 88. The switch 86 is normally closed and will be actuated into open position by a lever 90, pivotally supported at 91 on a bracket 92 which in turn supports a switch 86; when the pad 70 becomes empty.

A brake element 95 which carries a brake pad 96 to engage the periphery of the pad of material 76, is apertured at 97 to receive the inner end of a rod 98. An annular member 99 fixedly mounted upon a reduced portion of the inner end of the rod 98 is receivable in an annular recess 100 of the brake element 95 whereby the brake element may rotate with the flyer 10 while the rod 98 is held against rotation. A plurality of springs 102 have their adjacent ends secured at equally spaced positions to apertured flanges 103 of the brake element 95. There are four springs 102 and they extend substantially the full length of the frame or flyer 10; that is, the channel members 18 thereof where their right hand ends are secured to suitable brackets 104 (Fig. 1). The springs 102 are identical in structure and are expanded to create a given force therein which is applied to the pad 70 through the brake element 95 and its brake pad 96. Sheet metal guides 105 mounted on the channel members 18 and extending longitudinally thereof partially surround the springs as illustrated in Fig. 2.

The rod 98 extends axially through the shaft 19 and the bearing member 11 where the outer end of the rod is provided with a handle 107. A control element 108 mounted on the bearing member 11 has a flat under-surface 109 to be engaged by a flattened portion 110 of the rod 98 to hold the rod against rotation during rotation of the flyer 10. An associated element 111 mounted on

the bearing 11 cooperates with the element 108 in completing a substantially annular disc centrally apertured to guide the rod 98 in its longitudinal movement. A cutaway portion 112 is provided in the rod 98 adjacent the inner extremity of the flat surface 110 whereby the rod 98 may be rotated, when this portion is brought into registration with the flattened surface 109 of the element 108, to cause the element 108 to function as a latch to hold the rod with the brake element 95 in an outer position. The handle 107 is positioned to engage a roller 114 carried by the upper end of the lever 90, to rock the lever, to operate the switch 86 when the pad 70 is empty.

A suitable cover is provided for the flyer 10 including a main stationary portion 120 supported by the mounting brackets 14 and 16 and positioned therebetween, this portion surrounding approximately two thirds of the flyer, leaving an opening 121 through which access may be had to the flyer in mounting pads 70 singly in the flyer and making necessary adjustments for pads of various sizes. The opening 121 is closed by a door 123 provided with rollers 124 to ride upon a track 125 carried by the main cover 120.

During operation of the apparatus, let it be assumed that a full pad of material 70 is mounted in the frame of the flyer 10 and this material is threaded through the shaft 20 and directed to the means (not shown) which causes its longitudinal advancement. The brake element 95 rests on the periphery of the pad 70 and is forced thereagainst by the combined forces embodied in the springs 102. This force translated to the pad through the brake element 95 is at its maximum when the pad is full and will diminish gradually as the pad decreases in size through the paying off of the material therefrom. As a result, a constant tension is created in the material 76. While the material 76 is advanced longitudinally through the shaft 20, it is rotated about its longitudinal centerline by rotation of the flyer 10. This is brought about by the operation of the start switch 87 to energize the motor 82 to drive the shaft 79 which in turn will drive the flyer 10. This operation continues until the pad 70 becomes empty or approximately empty at which time the handle 107 of the rod 98 functioning as a cam will engage the roller 114 of the lever 90 and rock the lever clockwise until the switch 86 is actuated into open position, thus deenergizing the motor 82. The stop switch 88 is then actuated after which the operator pulls the rod 98 outwardly to the left (Figs. 1 and 4) until the shoulder adjacent the cutaway portion 112 in the rod engages the inner surface of the element 108, at which time the rod is rotated approximately 180° to lock the rod in its outermost position.

The operator then actuates the closest latch 33 or 34 to free the element 31 for removal whereby a core, which usually constitutes the central portion of the pad 70, may be removed and a new pad of material 70 installed in the flyer.

It is to be understood that the above-described arrangements are simply illustrative of the application of the principles of the invention. Numerous other arrangements may be readily devised by those skilled in the art which will embody the principles of the invention and fall within the spirit and scope thereof.

What is claimed is:

1. A material supplying apparatus for supporting a pad of tape-like material and rotating the material about an axis coincident with the longitudinal centerline of the material pulled from the

pad, the apparatus comprising a frame, means to support the frame for rotation about a given axis, power means to rotate the frame, means carried by the frame to rotatably support a pad of tape-like material as the material is withdrawn therefrom and advanced along a path coincident with the axis of the frame, a brake element movable relative to the support for the pad, spring means to force the brake element against the pad to apply a diminishing brake drag to the material comparable to the diminishing size of the pad to create a given tension in the material, and a rod movable relative to the frame concentric therewith for supporting the brake element for rotation with the frame.

2. A material supplying apparatus for supporting a pad of tape-like material and rotating the material about an axis coincident with the longitudinal centerline of the material pulled from the pad, the apparatus comprising a frame, means to support the frame for rotation about a given axis, power means to rotate the frame, means carried by the frame to rotatably support a pad of tape-like material as the material is withdrawn therefrom and advanced along a path coincident with the axis of the frame, a brake element movable relative to the support for the pad, spring means to force the brake element against the pad to apply a diminishing brake drag to the material comparable to the diminishing size of the pad to create a given tension in the material, and a rod movable relative to the frame concentric therewith for supporting the brake element for rotation with the frame, and means cooperating with the rod to hold the brake element free of the pad.

3. A material supplying apparatus for support-

ing a pad of tape-like material and rotating the material about an axis coincident with the longitudinal centerline of the material pulled from the pad, the apparatus comprising a frame, means to support the frame for rotation about a given axis, power means to rotate the frame, means carried by the frame to rotatably support a pad of tape-like material as the material is withdrawn therefrom and advanced along a path coincident with the axis of the frame, a brake element movable relative to the support for the pad, spring means to force the brake element against the pad to apply a diminishing brake drag to the material comparable to the diminishing size of the pad to create a given tension in the material, and means under the control of the brake element to render the power means ineffective when the pad becomes empty.
